UNITED STATES PATENT OFFICE.

JAMES A. BAZIN, OF CANTON, MASSACHUSETTS, ASSIGNOR TO ALFRED B. ELY, OF BOSTON, MASSACHUSETTS.

BRAIDING-MACHINE.

Specification of Letters Patent No. 11,512, dated August 8, 1854.

To all whom it may concern:

Be it known that I, JAS. A. BAZIN, of Canton, in the county of Norfolk and State of Massachusetts, have invented certain new and useful Improvements in Braiding and Plaiting Machines, of which the following is a full, clear, and exact description, reference being had to the annexed drawings, making part of this specification, in which—

10 Figure 1 is an isometric view of the machine. Fig. 2 an end view of one of the bobbins, the parts immediately connected therewith being seen in elevation. Fig. 3 is a plan of the parts connected with the drawing off motion. Fig. 4 a plan of the main body of the machine the bobbins and roses being removed. Fig. 5 is a diagram to illustrate the motion of the guide plates. Fig. 6 a portion of one of the bobbin carriers which will be referred to hereafter.

15 My invention consists in a movable guide plate, by which the motions of the bobbins are governed, the guide plate being operated by the bobbins themselves, by the use of 20 which the great friction which has heretofore operated so injuriously in machines of this character is measurably avoided, and the machine itself is greatly simplified.

25 My invention also consists in certain improvements in the details of the machine which will be more fully described and claimed hereafter.

30 To enable others skilled in the art to make and use my invention I will proceed to describe the method which I have adopted of carrying it out, setting forth first the general features of the machine,—then the individual improvements which I have added thereto, and lastly the combined operation 35 of all the parts.

40 A is the lower plate, B the upright posts, and C the upper plate of the machine, D the exterior, and D' the interior guide plates.

45 E are the shafts which support the roses or bobbin carriers; these carriers consist each of two parallel plates F and G, secured to the shaft E a short distance from each other, the former being of larger diameter than the latter and having upon its periphery notches *a*, of a sufficient depth to accommodate the shafts of the bobbin holders. Upon every alternate carrier the larger plate F is placed upmost, and upon the others it is beneath as seen in Fig. 1, and 55 they are so arranged that the peripheries of

the larger plates upon each shaft run in contact or very nearly so with the peripheries of the smaller plates of the adjacent carrier. The shafts E are all geared together by the cog wheels H one or more of 60 them being driven by a band M from a first mover K around pulleys L upon their extreme ends.

The bobbin holders are constructed as follows: N, Fig. 2 is the shaft or spindle 65 to which the plates *b* and *c* are attached; these plates fit one above and the other below the plates F and G of the bobbin carrier, and thus assist in retaining the bobbin holders in place.

70 *d* is a concave disk or plate fitted loosely to the stem N of the bobbin holder which passes through a hole in its center.

75 *f* are flat springs the ends of which are secured to the plate *d* as seen in Fig. 6 and through which the end of the shaft N passes, the screw *g* serving to confine the disk *d* to the stem N.

80 *h* are the side straps of the bobbin holders which are made in one piece and are secured to the disks *d* and thus connected with the stem N through the medium of the springs *f*, as seen in Fig. 1; these straps are bent around each other at their extremities so as to form forceps or spring guides *k*, 85 through which the thread from the bobbin passes, and thus a uniform and unvarying tension is put upon it.

90 *i* is a stretcher or box which serves to keep the sides of the bobbin holder apart from each other and the forceps closed. This peculiar construction of the bobbin holder enables it to bend over to one side and the other as it is carried around by the roses, the spring connection between the stem and the side straps of the bobbin holder allowing the latter to yield as the tension upon the forceps varies; and thus the thread is not needlessly unwound or injuriously loosened 95 when the bobbin is in the extremes of its path.

100 The movable guide plates will now be described, D is the exterior plate of a form represented in Fig. 4, it is supported upon the tops of the standards B and is held in place by pins in the stops of these standards, which enter the slots *m* in the plate which is thus allowed to vibrate a short distance in one direction and the other. D' is the interior plate which is connected with 105 110

the one just described by a vibrating bar represented by the line *n* in Fig. 5. This bar is pivoted at the point *o* to the frame of the machine, and is connected with the exterior plate at *p*, and with the interior plate at *q*; by this means the two plates are caused to move simultaneously and in contrary directions. The operation of these plates and the motion of the bobbins may be illustrated by the diagram Fig. 5 in which the red lines represent one position of the plates and the black lines the other. The path of the bobbins may be represented by the broken blue lines commencing with the plates in the position represented in black lines, the bobbins being retained upon the roses by the plates *b c*, Fig. 2, and the stem *N* projecting below the plates *D D'* by which they are guided in their paths, and kept closely pressed upon the peripheries of the carriers. Starting with the bobbins in the position represented in Fig. 1, three of them are at the points *r* Fig. 5 proceeding in the direction of the arrows at these points, and three of them at the points *s* proceeding in the contrary direction. At these points the bobbins being carried by the roses in circular arcs, strike against the movable plates at the points *r* and *s* and throw them into the position represented in red lines. The bobbins continue until they arrive at *r' s'*, when their stems *N* again move the plates into the position indicated in red, and thus the progress of the bobbins and the vibration of the plates continues.

P is a reel which may be used to carry a cord where it is desired to introduce such into the center of the braid. The cord from this reel passes beneath the plate *A* up through the tube *R* and the braid is formed around it by the strands from the bobbins.

S is a disk upon the top of tube *R*, the object of which is as follows. As the bobbins pass in toward the center of the machine the strands are liable to become so loose as to produce an uneven braid; to remedy this is the object of the disk *S*, which is made of such dimensions and placed at such a distance above the bobbins that they shall pass beneath it, and thus the strands are distended over the ends of the disk, and prevented from becoming injuriously loose. This contrivance in conjunction with the

spring in the bottom of the bobbin holder which allows the latter to yield as it passes the exterior of the curve, greatly conduces to the regularity and evenness of the product of my machine.

The braiding is accomplished at the bottom of the tube *T* whence it is conducted off over suitable rollers and drawn off by an appropriate contrivance at *U* and delivered to the reel *W*.

Y is a rod which is made to bear against the finished braid as it comes from the drawing off wheel *U*, and regulates its delivery to the reel. As these however are old devices and form no part of my present invention they need not be particularly described.

Z is a flat spring which carries a roller *x*, over which the finished braid is drawn as it passes out of the machine by which means a constant yielding tension is put upon the braid, one half of the strands being alternately tightened and loosened, as the bobbins revolve through opposite portions of their paths, and a much more even braid is produced than where a uniform tension has been placed upon all the strands as they leave the bobbins.

What I claim as my invention and desire to secure by Letters Patent is—

1. The above described movable guides *D*, *D'*, constructed and operating in the manner and for the purpose substantially as described.

2. I claim the method herein described of constructing the bobbin holders, the parts which carry and guide the thread being connected with the stem by means of springs *f*, which enables the bobbins to yield without permitting the strand to render too freely.

3. And I also claim in combination with the above method of constructing the bobbin holders, the herein described method of drawing off the finished braid over the spring plate *Z*.

4. I claim the disk, *S* operating in the manner substantially as described and for the purpose set forth.

JAMES A. BAZIN.
